UNITED STATES PATENT OFFICE

96,081

DESIGN FOR A SHORT AND TOP COMBINATION UNDERWEAR SUIT FOR MEN

Louis Arons, Chicago, Ill.

Application March 20, 1935, Serial No. 55,968

Term of patent 14 years

To all whom it may concern:

Be it known that I, Louis Arons, a citizen of the United States of America, residing at 30 South Clark Street, Chicago, Illinois, have invented a new, original, and ornamental Design for a Short and Top Combination Underwear Suit for Men, of which the following is a specification, reference being had to the accompanying drawing, forming a part thereof.

The figure is a perspective view of my short and top combination underwear suit for men embodying my design, the design being the same both front and back.

I claim:

The ornamental design for a short and top combination underwear suit for men substantially as shown and described.

LOUIS ARONS.
